UNITED STATES PATENT OFFICE.

OSMUND M. JORSTAD, OF EAST PITTSBURGH, PENNSYLVANIA, ASSIGNOR TO WESTINGHOUSE ELECTRIC AND MANUFACTURING COMPANY, A CORPORATION OF PENNSYLVANIA.

OVERHEAD TROLLEY SYSTEM.

Application filed April 7, 1922. Serial No. 550,361.

To all whom it may concern:

Be it known that I, OSMUND M. JORSTAD, a citizen of the United States, and a resident of East Pittsburgh, in the county of Allegheny and State of Pennsylvania, have invented a new and useful Improvement in Overhead Trolley Systems, of which the following is a specification.

My invention relates to overhead trolley systems and it has particular relation to those systems having relatively long distances between supporting towers or structures.

One object of my invention is to provide an overhead trolley system, adapted for railway work, that may properly employ the same size and weight of towers, or supporting structures, on curves that are employed on tangent portions of the track.

Another object of my invention is to provide an overhead trolley system of trolley construction having the main supporting structures an equal distance apart, regardless of the degree of curvature in the track.

Another object of my invention is to provide an overhead trolley system that will have all the vertical load carried by the main supporting structures or towers and all horizontal load taken by posts, independent of the main supporting structures.

Still another object of my invention is to provide an overhead trolley system that will be simple, economical and rugged in construction and positive and reliable in operation.

Briefly speaking, my invention consists in suspending the main cable, or a messenger cable, from the main supporting structures, or towers, and employing pull-off posts at suitable intervals between the towers to provide for the horizontal load upon the trolley system at curved portions of the track.

For a better understanding of my invention, reference may be made to the accompanying drawing,—

Figure 1 of which is a plan view of an overhead trolley system constructed in accordance with my invention;

Fig. 2 is a plan view, similar to that of Fig. 1, but on a considerably larger scale;

Figs. 3 and 4 are views, in side elevation, of portions of the trolley system illustrated in Fig. 1 of the drawing;

Fig. 5 is a view in end elevation and in section, taken along the line 5—5 of Fig. 2; 55

Fig. 6 is a side elevational view of a modified form of overhead trolley system constructed in accordance with my invention.

Referring to Figs. 1 to 5, inclusive, of the drawing, a plurality of overhead contact wires 1, 2 and 3 are supported by means of messenger cables 4, to which they are attached by means of a plurality of hangers 5. The messenger cables 4 are each supported 65 by means of a main cable 6 that is secured to a plurality of towers or main supporting structures 7, 8, 9 and 10 by means of suitable insulators 11. The structures 7, 8, 9 and 10 are of the same size, shape and 70 weight and any of them may be employed on curved portions of the track as well as on tangent portions.

The combined horizontal or radial pull of the contact wires 1, 2 and 3, messenger cables 4 and main cables 6 is carried to ground by means of a plurality of pull-off wires 12 and pull-off posts 13 which are positioned at the quarter points between towers and at the outer side of the track having the 80 least degree of curvature. Suitable insulators 14 are positioned in the pull-off wires 12 to insulate one contact wire and its supporting cable 6 and messenger cable 4 from another contact wire where such insulation 85 is considered desirable. Steady strains 16 (see Fig. 5) are provided at the posts 13 for more rigidly securing the contact wires 1, 2 and 3 in their proper horizontal positions. 90

Fig. 4 illustrates the manner in which the horizontal pull of the trolley system is transmitted to ground at points where the contact wire 1 and messenger cable 4 are interchangeable. Such a system is fully described in the patent application of P. M. McGee, Serial No. 527,593, filed Jan. 7, 1922, and assigned to the Westinghouse Electric & Manufacturing Co. 95

By having the horizontal stress carried by 100

the pull-off posts 13, instead of the towers 7, 8 and 9, a great saving is effected in the weight of the tower structures. As the highest of the pull-off wires 12 is substantially six feet below the insulators 11 on the supporting towers, the turning moment caused by the horizontal curvature in the trolley system is lessened by the reduced lever arm at which the horizontal force acts and thus the guide posts 13 need not be made to withstand as great a load as the main structures would be required to withstand if the horizontal stress were carried by the main supporting structures. It is also advantageous to have all the towers of the same size and shape, thereby effecting a saving when they are manufactured in large quantities and also eliminating the possibility of incorrect shipments of towers of dissimilar types to points where the system is being constructed.

The trolley system shown in Fig. 2 illustrates the tower 10 as carrying a portion of the horizontal stress of the overhead trolley system. It is, of course, appreciated that a portion of the horizontal stress of the trolley system might be carried by the towers without greatly increasing their weight. In fact, it might prove advantageous to permit the towers to carry some horizontal load, if the horizontal load be sufficiently small that it would not be the governing feature of the design of the tower. However, such a system is intended to be within the scope of my invention if the greater portion of the horizontal stress is carried to ground by means corresponding to the pull-off posts 13.

Referring to Fig. 6 of the drawing, which illustrates a simplified form of overhead trolley system in which the distance between spans is such as to make it unnecessary to employ a main cable 6, the messenger cables 4 are attached directly to the main supporting structures 9 and 10 by means of insulators 11 and the horizontal stress in the messenger cables 4 is carried to ground by means of the pull-off wires 12 and pull-off posts 13.

It is to be understood that slight variations in the distance between towers may be made without departing from the spirit of my invention, but it is considered most advantageous to space the towers equal distances apart on both the tangent and curved portions of the tracks.

By spacing the towers relatively great distances apart, an engineer will have a better vision of the track than has heretofore been secured where overhead trolley systems have been employed on curves.

While I have illustrated my invention in the preferred form, it is apparent that modi-

fications may be made in the arrangement of the system without departing from the spirit of my invention. I desire, therefore, to be limited only by the scope of the appended claims.

I claim as my invention:—

1. In an overhead trolley system, the combination with a plurality of main supporting structures, of a contact conductor, means comprising a messenger conductor for supporting said contact conductor, means for securing said messenger conductor to said structures, and means independent of said structures for taking a portion of the horizontal pull of said messenger conductor. 70

2. In an overhead trolley system, the combination with a plurality of main supporting structures, of a contact conductor, means comprising a messenger conductor for supporting said contact conductor, means for securing said messenger conductor to said structures, and means independent of said structures for taking all of the horizontal pull of said messenger conductor. 80

3. In an overhead trolley system, the combination with a plurality of main supporting structures, of a contact wire, means comprising a messenger cable for supporting said wire, means for securing said messenger cable to said structure, and means comprising a pull-off post for transmitting the horizontal pull of said messenger cable to ground. 90

4. In an overhead trolley system, the combination with a plurality of main supporting structures, of a contact conductor, means for vertically supporting said conductor by attaching it to said structures, and means independent of said structures for transmitting a portion of the horizontal pull of said conductor to ground. 100

5. In an overhead trolley system, the combination with a plurality of main supporting structures, of a contact wire, means for vertically supporting said wire by attaching it to said structures, and means independent of said structures for transmitting the horizontal pull of said wire to ground. 105

6. In an overhead trolley system, the combination with a plurality of main equally spaced supporting structures, of a contact wire supported by said structures, and means independent of said structures for taking all of the horizontal pull of said wire where said structures are in angular relation. 115

7. In an overhead trolley system, the combination with a plurality of equally spaced main supporting structures, of a contact wire supported vertically by said structures, and means other than said structures for sufficiently removing the horizontal pull of said contact wire from said structures to 120

- maintain the same spacing between said structures on curved as upon tangent portions of the system without changing the weight of said structures. 65
- 5 8. In an overhead trolley system, the combination with a plurality of equally spaced main supporting structures, of a contact wire supported vertically by said structures, and independent means comprising a plurality of pull-off posts for sufficiently removing the horizontal pull of said contact wire from said structures to maintain the same spacing between said structures on curved as upon tangent portions of the system without changing the weight of said structures. 70
- 10 9. In an overhead trolley system, the combination with a plurality of main supporting structures, of a contact wire, means for supporting said wire by attaching it to said structures and means comprising a plurality of posts mounted at the quarter points between said structures, for balancing the radial pull of said contact wire on curves. 75
- 15 10. In an overhead trolley system, the combination with a plurality of main supporting structures, of a contact wire, a messenger cable for supporting said wire, a plurality of hangers for mechanically connecting said messenger cable to said wire, means for mounting said messenger cable on said structures, a post positioned between said structures and means comprising a pull-off wire for mechanically connecting said contact wire to said post. 80
- 20 11. In an overhead trolley system, the combination with a plurality of main supporting structures, of a contact wire, a messenger cable for supporting said wire, a plurality of hangers for mechanically connecting said messenger cable to said wire, means for mounting said messenger cable on said structures, a plurality of posts positioned between said structures, and means comprising a plurality of pull-off wires for mechanically connecting said contact wire and messenger cable to said posts. 85
- 25 12. In an overhead trolley system, the combination with a plurality of main supporting structures, of a contact wire, a messenger cable, means for mechanically connecting said wire to said messenger cable, a main cable, means for attaching said main cable to said structures, and means independent of said structures for transmitting the horizontal pull of said wire, messenger cable and main cable to ground. 90
- 30 13. In an overhead trolley system, the combination with a plurality of main supporting structures, of a contact wire, messenger cable, means for mechanically connecting said wire to said messenger cable, a main cable, means for attaching said main cable to said structures, and means comprising a post independent of said structure for transmitting the horizontal pull of said wire, messenger cable and main cable to ground. 95
- 35 14. In an overhead trolley system, the combination with a plurality of main supporting structures, of a contact wire, a messenger cable, means for mechanically connecting said messenger cable to said wire, a main cable, means for attaching said main cable to said structures, and means comprising a post independent of said structure for transmitting the horizontal pull of said wire, messenger cable and main cable to ground. 100
- 40 15. In an overhead trolley system, the combination with a plurality of main supporting structures, of a contact wire, a messenger cable, means for mechanically connecting said messenger cable to said wire, a main cable, means for attaching said main cable to said structures, and means comprising a plurality of posts spaced at the quarter points between said structures for transmitting the radial pull of said wire, messenger cable and main cable to ground. 105
- 45 16. In an overhead trolley system, the combination with a plurality of main supporting structures, of a contact wire, a messenger cable, a plurality of hangers for suspending said wire from said messenger cable, a main cable for supporting said messenger cable, means for attaching said main cable to said structures, and means comprising a post between said structures and a pull-off wire for transmitting the radial pull of said main cable to said post. 110
- 50 17. In an overhead trolley system, the combination with a plurality of main supporting structures, of a contact wire, a messenger cable, a plurality of hangers for suspending said wire from said messenger cable, a main cable for supporting said messenger cable, means for attaching said main cable to said structures, means comprising a post between said structures and a plurality of pull-off wires for transmitting the radial pull of said main cable and said messenger cable to said post. 115
- 55 18. In an overhead trolley system, the combination with a plurality of main supporting structures, of a contact wire, a messenger cable, a plurality of hangers for suspending said wire from said messenger cable, a main cable for supporting said messenger cable, means for suspending said main cable from said structures, means comprising a plurality of posts between said structures, and means comprising a plurality of pull-off wires for transmitting the radial pull of said contact wires, messenger cable and main cable to said posts. 120
- 60 19. In an overhead trolley system, the

combination with a plurality of main supporting structures, of a plurality of conductors each of which alternately serves as a contact wire and messenger cable, means for supporting said conductors one from another, a main cable, means for suspending said main cable from said structures, means for suspending said conductors from said

main cable, and means comprising a post for transmitting the radial pull of said conductors and main cable to ground. 10

In testimony whereof, I have hereunto subscribed my name this 27th day of March 1922.

OSMUND M. JORSTAD.
